UNITED STATES PATENT OFFICE.

MILTON K. AKERS, OF TROY, OHIO, ASSIGNOR TO THE TROY METAL PRODUCTS COMPANY, OF TROY, OHIO, A CORPORATION OF OHIO.

DESIGN FOR A FRAME FOR FOOD MIXER.

Application filed March 8, 1923. Serial No. 5,416. Term of patent 14 years.

To all whom it may concern:

Be it known that I, MILTON K. AKERS, a citizen of the United States of America, residing at Troy, in the county of Miami, State of Ohio, have invented a new, original, and ornamental Design for Frame for Food Mixer, of which the following is the specification, reference being had to the accompanying drawing, forming a part thereof.

The single figure of the drawing is a view in the nature of a perspective, the view being taken from one side, showing the design of this invention.

I claim:

The ornamental design for a frame for food mixer, as shown.

MILTON K. AKERS.
